THOMAS H. KANE, OF YOUNGSTOWN, OHIO, ASSIGNOR TO TRUSCON STEEL COMPANY,
OF YOUNGSTOWN, OHIO, A CORPORATION OF MICHIGAN

STRUCTURAL MATERIAL

Application filed December 21, 1925. Serial No. 76,665.

The present invention relates to structural materials for buildings and particularly to materials adapted for roofing and for flooring intended to support light loads.

5 Among the objects of the invention is a material for the purposes specified which is easily and economically made and used and which contains little or no excess material.

Another object is a material for the purpose indicated which shall be very light in weight but sufficiently strong and which may be produced from light weight and gauge materials.

With these and other objects in view as 15 will more clearly hereinafter appear, the invention consists broadly in a rolled metal sheet of small thickness having secured to one side thereof stiffening ribs formed of similar material by means of which the sheets 20 are adapted to be supported upon suitable joists or the like. The sheets preferably have secured to the other side a moderately thick layer of fiber-board or other suitable sound and heat insulating material, and this may 25 be further covered with waterproofing material, if desired, although both of these layers may be omitted.

Reference should be made to the accompanying drawing, in which:—

30 Fig. 1 shows a section of one form of the material across the ribs;

Figs. 2 to 6 show similar sections of as many modifications thereof; and

Fig. 7 shows a fragmentary plan view of 35 Fig. 6 from below.

The present invention may be regarded as an improvement over that shown in application Serial Number 39,227, filed June 24, 1925, for "building construction" by Julius Kahn.

40 Referring to the drawings, (Figs. 1 and 2), 10 indicates a continuous thin flat rolled sheet of metal having secured to one side thereof as by welding the ribs 11 and 12, these latter being formed of similar sheet metal folded 45 back upon itself to form a rib of I-section as at 11 or T-section as at 12.

Upon the other side of the sheet 10 may be secured, as by cementing, a comparatively thick sheet or layer 13 of a heat and sound 50 insulating material such as fiber-board, which

acts as a compression member when the material is subjected to loading, the sheet metal 10 and ribs being placed under tension.

Fig. 3 shows a somewhat different form of that shown in Fig. 2. In this form of material, the formed sheet metal rib 12^a is secured to metal sheet 10^a, by forming in the latter parallel folds 15, spaced apart the width of the double flange on rib 12^a, and crimping said folds 15 over the edges of the double flange as at 16. In this figure is also shown the insulating layer 13.

Fig. 4 shows a form of material in which a rib 12^b of I-section is secured in the same manner as is shown in Fig. 3, the folds being indicated at 15^a and the crimping of the folds at 16^a.

Fig. 5 shows a form in which the rib is secured as in Figs. 3 and 4, a different form of rib being shown. In this form of rib, the 70 sheet metal 20 is formed into T-section but the edge of the web portion 21 encloses a solid rib 22.

Fig. 6 shows a modification of the method of securing the rib to the sheet. In this figure 75 the sheet 10^c is provided with tongues 30 punched out of the body thereof and spaced apart the width of the double flange 31 of the formed rib. These tongues 30 are then pressed down over the edges of the double 80 flange to secure the rib in place.

Having now described the invention and the preferred forms of embodiment thereof, it is to be understood that the said invention is not to be limited to the specific details herein set forth but only by the scope of the claims which follow.

Claims:

1. A roofing or flooring material comprising a continuous sheet of metal, a plurality of stiffening ribs therefor formed of sheet metal folded to I or T shape, and means for securing a double flange of said ribs to one side of said sheet, said means comprising folds formed of the metal of said sheet crimped over the edges of said double flange.

2. A roofing or flooring material comprising a continuous sheet of metal, a plurality of stiffening ribs therefor formed of sheet metal folded to I or T shape, means for se-

curing a double flange of said ribs to one side of said sheet, said means comprising folds formed of the metal of said sheet crimped over the edges of said double flange, 5 and a heat insulating layer secured to the other side of said sheet.

THOMAS H. KANE.
